UNITED STATES PATENT OFFICE

139,831

DESIGN FOR A COMBINATION DESK UNIT

Emanuel R. Posnack, New York, N. Y.

Application September 2, 1944, Serial No. 115,169

Term of patent 14 years

(Cl. D74—1)

To all whom it may concern:

Be it known that I, Emanuel R. Posnack, a citizen of the United States, resident of the Borough of Queens, in the county of Queens and city and State of New York, have invented a new, original, and ornamental Design for Combination Desk Unit, of which the following is a specification, reference being had to the accompanying drawing, forming part thereof.

The figure is a perspective view of the combination desk unit showing my new design, the essential features of which are disclosed in full lines, the broken lines indicating a pad member and a weighted member resting upon the portion of the pad member extending within the forward compartment of the unit.

nation desk unit showing my new design, the essential features of which are disclosed in full lines, the broken lines indicating a pad member and a weighted member resting upon the portion of the pad member extending within the forward compartment of the unit.

I claim:

The ornamental design for a combination desk unit, substantially as shown and described.

EMANUEL R. POSNACK.
